UNITED STATES PATENT OFFICE.

CHARLES CAMMACK, OF CROSSETT, ARKANSAS.

SILO-DOOR.

1,123,680.

Specification of Letters Patent.

Patented Jan. 5, 1915.

Application filed August 8, 1914. Serial No. 855,797.

To all whom it may concern:

Be it known that I, CHARLES CAMMACK, a citizen of the United States, residing at Crossett, in the county of Ashley and State of Arkansas, have invented certain new and useful Improvements in Silo-Doors, of which the following is a specification, reference being had to the accompanying drawings.

10 This invention relates to certain improvements in silo doors, and an object of the invention is to provide a novel and improved device of this general character whereby the door may be applied into operative position 15 with convenience and facility and whereby the door, after being so applied, may be effectively maintained in operative position.

The invention also has for an object to provide a device of this general character 20 including a novel and improved hinge for a silo door whereby the door may be easily and readily swung outwardly through the door opening so that access may be had to the interior of the silo.

25 The invention consists in the details of construction and in the combination and arrangement of the several parts of my improved silo door, whereby certain important advantages are attained and the device is 30 rendered simpler, less expensive and otherwise more convenient and advantageous for use, all as will be hereinafter more fully set forth.

The novel features of the invention will be 35 carefully defined in the appended claim.

In order that my invention may be the better understood, I will now proceed to describe the same with reference to the accompanying drawings, wherein—

40 Figure 1 is a fragmentary view in elevation of a silo, illustrating a door secured thereto in accordance with an embodiment of my invention; Fig. 2 is a sectional view taken substantially on the line 2—2 of Fig. 45 1; Fig. 3 is an enlarged view, partly in elevation and partly in section, illustrating the engagement of the hinge member with the silo, as herein embodied; Fig. 4 is an enlarged elevational view of the catch herein included; and Fig. 5 is an enlarged elevational view of the bracket, herein included, carried by the door.

As disclosed in the accompanying drawings, 55 1 denotes a fragment of a silo provided with a door-way 2, and 3—3 denote

the jambs secured along the edges of the door-way 2.

As each door is substantially identical in construction, it is thought that a description of one together with its concomitant 60 parts will suffice for the purpose of disclosure.

4 denotes a door adapted to be inserted through the door-way 2 and to overlie the jambs 3, in a manner which is believed to 65 be self-evident, and the outer faces of the door are provided with the longitudinally disposed parallel bars 6, the intermediate bar being disposed at substantially the transverse center of the door. 70

Secured to one of the jambs 3 substantially midway of a door-way or opening is a bracket 7 provided with the outstanding spaced arms 8 provided with alined openings 9 through which is adapted to be directed a pintle 10, said pintle being also adapted to be directed through the barrel or sleeve 11 formed at one extremity of the hinge member 12. 75

As herein embodied, the portion of the 80 hinge 12 immediately adjacent the barrel or sleeve 11 is disposed on a segment of predetermined radius, while the opposite extremity thereof is elongated and terminates in a barrel or sleeve 12 adapted to be received 85 between the arms 14 of the bracket 15 secured to the intermediate bar 6, said arms being provided with alined openings 16 through which is adapted to be directed the pintle 17, said pintle 17 being also adapted 90 to be directed through the sleeve or barrel 12. By this arrangement, it will be readily perceived that the door 4 is conveniently and effectively maintained in hinged position relative to the silo 1, and said hinge is 95 of a portable type, whereby the same may be applied with convenience and facility at the time required. In order to maintain the door effectively in closed position, I employ the elongated member 18 having one end 19 100 angularly disposed and pivotally engaged with a jamb 3 through the medium of a horizontal pivot, as indicated at 20, whereby said member may be swung upwardly, and the opposite end portion of such member is adapted to be received within the catch 21 carried by the opposite jamb 3 105 with the intermediate portion of said elongated member resting upon the upper arm 14, the free extremity of such arm being up- 110

- turned, as indicated at 22, whereby it will be perceived that the door 4 will be effectively maintained in closed position. It will also be observed that the member 18 serves as a step or bar adapted to coact with the immovable members 22 positioned above and below the door opening 2 to afford a ladder construction, for a purpose which is believed to be self-evident.
- 10 From the foregoing description, it is thought to be obvious that a silo door constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from 20 the principles and spirit thereof and for this reason I do not wish to be understood as limiting myself to the precise arrange-

ment and formation of the several parts herein shown in carrying out my invention in practice.

I claim:

The combination with a silo having a door-way and a door seatable against the inner side of the silo, of a bracket secured to the door at substantially the center of the outer face thereof, said bracket comprising vertically aligned arms, the uppermost of said arms being upturned, a hinge member for the door detachably engaged between the ears of the bracket, and a locking member for the door disposed across the doorway and coacting with the upturned portion of the upper arm of the bracket.

In testimony whereof I hereunto affix my signature in the presence of two witnesses.

CHARLES CAMMACK.
